ROTARY GOLD CONCENTRATOR

Daniel B. Cave, Lincoln, Nebr., assignor, by direct and mesne assignments, of one-third to Allen P. Furgason, one-third to Emery F. Ozenbaugh and Edgar Overton, and one-third to Paul V. Ashton, all of Lincoln, Nebr.

Application January 27, 1934, Serial No. 708,684

2 Claims. (Cl. 209—44)

My invention relates to rotary gold concentrators, its primary object being the provision of a concentrator which will operate efficiently in separating microscopic gold from goldbearing sand.

5 Another object is the provision of a slowly rotating drum so designed that it will materially increase the distance through which the gravel must pass over screens to separate the gold from the sand.

10 Another of my objects is the provision of a concentrator which will not only separate the gold and gold ore from the sand but which will segregate the finer from the coarser particles for convenience in milling the ore.

15 Another of my objects is the provision of a separator which is so designed as to almost entirely eliminate eddy currents or other disturbances in the water having microscopic particles suspended therein.

20 Having in view these objects and others which will be pointed out in the following description, I will now refer to the drawings, in which

Figure 1 is a view partly in elevation and partly in section showing my rotary gold ore separator.

25 Figure 2 is a top plan view of this same separator, the shield being omitted to more clearly disclose the drum.

30 Figure 3 is a cross sectional view of the separator.

Figure 4 is a fragmentary view of a portion of the drum showing particularly the means for transferring the sand from compartment to compartment.

35 Figure 5 is a view in sectioned perspective showing the pickup scoop at the intake to the drum.

Figure 6 is a view in perspective showing the skimmer adjacent to the discharge end of the drum.

40 Figure 7 is a view in perspective showing the discharge mechanism for discharging the spent sand after it has passed through the drum.

Figure 8 is a perspective view with parts broken away of the feed trough of the separator.

45 Figures 5, 6 and 7 are axially aligned to show the relative positions of the parts with respect to each other and with respect to the organization.

The mechanism includes a rotary drum which is mounted on a shaft 10 to be driven through a worm or similar gear 11. The drum consists of a plurality of disks 12 which are rigidly secured to the shaft 10 and which are rigidly tied together by means of bolts 13. Hoops 14 are secured to the disks 12 at their peripheries. The entire drum is surrounded by screens through which the finer

material may pass during the rotation of the drum. The screens 15 are of fine mesh, the screens 16 are of medium mesh while the screens 17 are sufficiently large in mesh to permit the passage of the coarsest ore particles in the sand. The drum is designed for slow rotation in a tank 18 containing water. This tank is divided into three compartments by means of the parts 19. The ore passing through the screens 15 will thus fall into the first compartment, the medium sized ore will fall into the second compartment and the coarsest of the ore will require milling before the particles of gold can be separated from it and this is true to some extent of the medium ore. The finest of the ore can usually be treated without the preliminary milling. The arrangement as above described facilitates the separation of the different ores and simplifies the milling process. The arrangement can, however, be extended by separating the ore into as many different grades as might be desired.

The tank 18 is provided with a receiving compartment 20 into which the goldbearing sand is deposited. The pickup scoop 21 is shown in Figure 5 in operation in the receiving compartment 20. This scoop is secured to rotate with the shaft 10. It extends radially in opposite directions from the shaft 10 and is provided with two intakes 22 at its opposite ends. Owing to the abrasive action of the sand, the intakes are shielded by means of removable steel knives 23. The sand which is scooped up into the intake 22 is forced towards the axis of rotation, this being due largely to the weight of the sand which is first carried up by the scoop 21 and then permitted to drop. The shaft 10 is hollow at its ends but the middle portion of the shaft 10 is either solid or it is blocked off from the hollow end portions. Since the scoop is provided with two intakes 22, the hollow portion of the shaft must have a septum 24 to prevent the material from dropping through to the bottom intake. The pressure of the wet sand entering the intakes 22 thus forces it into the hollow portion of the shaft which is provided with two diametrically opposite discharge apertures 25. These apertures 25 are positioned in the first compartment of the drum so that the slow rotation of the drum will cause the material to roll on the inner surface of the first screen 15 to separate the finest portions of the gold from the sand.

The arrangement is such that the material entering the drum must pass through a complete revolution before it can enter the next compartment. For this purpose each disk is provided with an opening 26, all of these openings being in

alignment. Connecting each pair of disks 12 is a baffle 27 which extends from the rearward edge of one aperture 26 to the forward edge of the next aperture 26. Baffles 27 prevent the material 5 from falling back into the compartment from which it is to be discharged. As a result the material in each compartment of the drum moves on to the next compartment when the baffles 27 and the apertures 26 are in their bottom positions. 10 The material is thus forced to travel the entire interior surface of the screen of one compartment before it can be discharged into the next adjacent compartment.

The material is thus passed along with the 15 separation of its finest materials as it passes through each compartment in succession. The finer particles are deposited in the various compartments of the tank 18 so that by the time the last compartment of the drum is reached, the material 20 has been not only reduced in quantity but nearly all of the valuable portions of the ore have been extracted from it. The material then is in condition to be discarded. The last compartment of the drum is provided with a skimmer 28 which 25 continuously divides the material in that compartment. The skimmer is provided with two diametrically opposite apertures 29 communicating with similar apertures 30 in the discharge mechanism. This discharge member is similar to 30 the scoop 21 in that it is secured to a hollow portion of the shaft 10 to rotate therewith. The water and spent sand entering the aperture 30 are forced toward the axis of rotation and into the hollow portion at the discharge end of the shaft 35 10. This hollow portion is also provided with a septum 31 to prevent the falling of the spent sand to the opposite end of the discharge mechanism. The spent sand suspended in water is thus forced out through the hollow portion at the discharge 40 end of the shaft 10.

The drum is surrounded by a stationary shield or jacket 32 except for its top portion. This shield terminates in its lower portion in a relatively narrow spout 33 for discharging the materials 45 from the screen into the water in the tank 18. As a result the rotation of the drum, even though slow, will set up disturbing currents in the water but these currents cannot be communicated to the body of water in the tank 18. Owing to the extremely minute size of the particles of gold discharged through the screens, it is exceedingly important that no disturbing currents be set up in the water which would retard the settling of the gold particles in the water.

50 The screens employed for this purpose are of exceedingly fine mesh and in some cases there is a tendency for them to become clogged up. For obviating this difficulty I provide a rotary brush 34 which rests against the upper surface of the screen. The brush 34 is mounted on a shaft which is journaled at its ends in a support as shown in Figure 1. The rotation of the drum will thus be communicated to the brush which rotates in contact with the screen throughout its entire 55 length to drop any particles which might tend to clog the openings in the screen.

It is desirable that the water level in the two compartments be the same. The water is introduced into the receiving compartment and I have 60 provided a structure as shown in Figure 8 for permitting the flow of the water into the main chamber without permitting the flow of the goldbearing sand into the drum. The chamber wall 35 is apertured and another wall 36 is inserted in the 65 chamber 20 underneath the bearing of the shaft 70 75

10. The wall 36 is also apertured. The two walls 35 and 36 are spaced apart and the space between them is filled with gravel to function as a filter for preventing the flow of anything but water. The water thus readily seeks its level in both chambers.

In operation, power is supplied through the worm drive to the shaft 10 and the compartment 10 receives the goldbearing sand. Water also is added to keep at least part of this sand in suspension. The pickup scoop forwards the material into the first compartment from whence it is discharged into the next compartment after one complete revolution of the drum. At the same time additional material passes into the first compartment to take the place of that which is discharged. After a sufficient number of revolutions each compartment of the drum will contain some of the material. The drum itself is of a relatively small diameter so that a slow rotation of the drum 20 will cause a rolling of the material on the screen. After the material has been spent it leaves the machine through the discharge outlet in the shaft 10 and from thence it may be conducted to any desired place. During the rotation of the drum 25 the finer particles of material in gradually increasing size will pass out through various screens 15, 16 and 17 to be segregated in the various compartments in the bottom of the tank 18. The lower portion of the drum is entirely submerged in 30 water so that all of the material in the drum is in a fluent condition. Owing to surface tension the microscopic particles of gold tend to remain in suspension especially when there is a disturbance in the water no matter how slight. The 35 water beneath the drum is kept in quiescent condition and not subject to disturbance from the rotation of the drum due to the fact that the shield 32 confines the disturbance to the annular space 40 between the drum and the shield. After the fine 45 particles of gold and gold ore have passed through the funnel 33 they are permitted to settle with little or no disturbance of the water medium in which they are suspended.

The entire machine is compact and of light 45 weight as compared with the prior machines. It is designed for use in sandy localities in which the sand is found associated with small and minute particles of gold. As the rejected sand accumulates, the entire machine may readily 50 be moved a sufficient distance to avoid the accumulation.

The material passing through the drum is maintained in a fluent condition. The rotation 55 of the drum results in a rolling of the goldbearing sand with just sufficient agitation to keep all but the heaviest particles of sand suspended in the water. When the material is discharged with a certain amount of water, it may be conducted to a settling tank where the spent sand may be 60 separated by settling from the water. The object is to use the water over and over again for two reasons. In localities where there is a scarcity of water or where the water must be obtained from deep wells, the cost of conducting 65 the water to the machine is apt to be greater than the cost of decanting it from a settling basin. The water from the settling basin is apt to have a small amount of gold which remains in suspension in the water. The water passing repeatedly through the drum thus accumulates gold in suspension and this gold on sufficient concentration will settle more readily than it would if the gold occurs in smaller quantities.

Having thus described my invention in such 75

full, clear, and exact terms that its construction and operation will be readily understood by others skilled in the art to which it pertains, what I claim as new and desire to secure by Letters Patent of the United States is:

5 1. In a concentrator for separating ore from gold-bearing sand, a water tank having an open top, an intake tank for receiving water and gold bearing sand, means for maintaining a uniform 10 water level in both of said tanks, a shaft extending across both of said tanks, said shaft being hollow in its end portions, a drum in said water chamber and secured to said shaft to rotate therewith, a screen surrounding said drum, disks 15 dividing said drum into a plurality of compartments, a pickup device in said intake tank secured to said shaft to rotate therewith, said pickup device consisting of a pair of diametrically opposed scoops communicating with conduits for conducting the material to the hollow portion at the intake extremity of said shaft, a 20 septum in the hollow portion at the intake extremity of said shaft for dividing the material picked up by said two scoops, the hollow portion at the intake extremity of said shaft being provided with two apertures for conducting the 25 material into the first of the chambers of said drum, means associated with said disks for conducting the material in each compartment to the next adjacent compartment at every com-

plete revolution of said drum, and means at the discharge end of said drum for discharging the spent material from the last of the compartments of said drum through the hollow portion at the outlet extremity of said shaft after the gold and gold ore has been extracted therefrom.

5

2. In a concentrator for separating gold from goldbearing sand, a washing tank, a horizontal shaft in the upper part of said tank, a foraminous drum secured to said shaft to rotate therewith, a receiving tank secured to said washing tank and to said shaft, said shaft being tubular in both of its end portions to provide intake and outlet conduits for the passage of sand into and out of said drum, said intake conduit extending 10 from said receiving tank into said washing tank, a rotatable scoop for picking up the sand from said receiving tank to be conducted through said intake conduit into said drum, the contiguous walls of said washing and receiving tanks being 15 perforated and being spaced from each other to provide a chamber for receiving a filter layer of gravel, and a mechanism for discharging the spent sand, said mechanism including a septum in the discharge conduit of said shaft to divide 20 said discharge conduit into two chambers, a skimmer for dividing the spent sand, and a double scoop communicating with said skimmer and with the two chambers of said discharge conduit.

25
